UNITED STATES PATENT OFFICE

LOUIS L. DRIGGS, JR., OF NEW ROCHELLE, AND HENRY B. FABER, OF NEW YORK, N. Y.

FIXED AMMUNITION

Application filed January 8, 1929. Serial No. 331,127.

Our present invention relates to improvements in signalling systems, in which a cylinder containing a flare and a parachute, or similar signalling devices are propelled from a gun, or a firearm, and after the container has travelled a certain distance, a second explosion occurs, in which the signalling device is ejected from the container, and the parachute is released, and explodes the flare as it descends gently towards the ground.

With such apparatus the container referred to may be of sufficient weight to cause injury to persons or property in falling, and in such cases, it becomes desirable to cause the container to descend gently with the flare.

This may be accomplished by connecting both the container and the flare to the parachute, so that all three bodies will descend gently after the parachute has become distended, and the flare has been ignited in the usual way.

Our invention will be more fully understood after reference to the accompanying drawings, in which like parts are indicated by similar reference symbols throughout the several views, and in which,

Figure 1 is a diagrammatic view, showing the main cartridge case, and the container ejected therefrom.

Figure 2 shows the container after the secondary explosion with the parachute and flare ejected therefrom.

Figure 3 shows a similar view to Figure 2 at a later stage, but shows the parachute before it becomes distended.

Figure 4 is a diagrammatic view, showing the parachute distended, and the flare in operation, and the parachute, flare and container all in the position for descending.

Figure 5 shows a section through the cartridge case with the container therein, and with the parachute and flare.

Figure 6 shows a section along the line 6-6 of Figure 5, and

Figure 7 shows a section along the line 7-7 of Figure 5.

Figure 8 shows a section along the line 8-8 of Figure 5.

A represents diagrammatically the piece from which the main cartridge case is fired.

This piece may be of any suitable type of gun or pistol, such, for instance, as the muzzle loading firearm shown in our application Ser. No. 263,024, filed March 20, 1928, and entitled Improvements in firearms. In order to provide sufficient capacity for the cartridge case B, it is provided with an enlarged bore with a smaller stem B' of suitable size to project into the short barrel in which the cartridge case is fired. Contained in this cartridge is a projectile which comprises the container C, the flare D and the parachute E. The flare container and parachute are connected together by the wire or cable F, as shown in Figures 2, 3 and 4, to which the stays e are connected. This cable or wire may be provided with one or more shock absorbers f interposed between the parachute and either the container C or the flare D, or both. These shock absorbers may be of coiled wire, or other suitable type.

We have shown two such shock absorbers in Figure 3, and these may be desirable where the container or the flare are of large size or weight, but these may be dispensed with where the weights of the container and flare are comparatively small.

When the piece is fired, the container travels the predetermined distance before it, in turn, ejects the flare and the parachute, and, the parachute becoming distended, supports the flare and the container as they descend gradually towards the ground, all as illustrated diagrammatically in Figures 1 to 4. The details of construction of the container and the contents thereof used in this apparatus will now be described. These details are similar in many respects to the construction shown in our application filed March 20, 1928, Ser. No. 263,026, and entitled Improvements in firearms, but differs therefrom in minor respects only.

The construction of the main cartridge case, and the container and its contents are shown in detail in Figures 5 to 8, and will now be described.

The cartridge case B is preferably provided with a stem B' which slides into the barrel of the firearm A and is provided with an annular groove b' which engages the 100

spring latch for holding the cartridge case in the barrel, as shown in our application Ser. No. 263,026, aforesaid.

This stem is provided with an expansion chamber B^o into which the gases from the cartridge G are blown when the piece is fired.

It only requires a small blank cartridge to eject the projectile from the cartridge case, as will be hereinafter described.

10 In front of this chamber B^o , the cartridge case is flanged outwards, as at b , and in front of this flange, we provide the washers H, H' and H'', of which the center washer H' is preferably made of felt, or similar material, 15 and the other two of metal. In front of these washers is the cylindrical container C which is preferably made of aluminum, or other light metal, and has its forward end closed by the cup shaped cap I, which engages the forward end of the cartridge case, as shown in 20 Figure 5. Inside the rear end of this container is mounted the annular cup K which is closed at its forward end, and at its rear end is engaged by the flanged rear end c of the container C. In the center of this annular cup K, is a cylindrical cup M closed at its rear and having an annular flange m engaging the annular groove k of the cylindrical cup K, which part k is crimped to said 25 flange m , as shown in Figure 5.

The front end of the cup M is closed by a paper disk m' , and inside of the cup is an 30 ejecting charge M'. Projecting through the washers H, H' and H'' and into the ejecting charge M' is the primer N which is in the form of a hollow tube containing a slow burning fuse composition N' which fuse composition is ignited by the flame from the blank cartridge when the piece is fired, causing the container with the parts enclosed therein to be ejected from the cartridge case B.

After a predetermined delay, the fuse composition N' ignites the expelling charge M' and ejects the casing containing the flare composition and parachute, which are held in the container until the container has been ejected a predetermined distance from the casing.

In front of the annular cup K is a circular 35 washer O of felt, or other suitable material. Exterior to this washer, the container C is crimped inwards slightly, as at c' , to hold the annular cup K in place, as shown in Figure 5. In front of the washer O, the end p of the flare casing P is flanged inwards, leaving an opening p^o at the center of the flanged end.

This case for the flare composition may be made of cardboard, papier mâché, or the like, and is preferably in two or more layers. 40 Two layers are shown in Figure 5, but a single layer may be used, if desired, or three or more may be used, if desirable.

In the rear end of the flare chamber, we provide a layer of slow burning flare composition Q, which preferably has its rear face

q exposed to the flame from the expelling charge. This composition Q is first ignited, and in turn ignites the flare composition Q'.

In front of this slow burning flare composition is the flare composition Q', and the end of the flare casing P is closed by the metal cap R which is crimped over, or otherwise secured, to the front end of the flare casing, as shown at r in Figure 5.

The wire or cable F has its end f^o secured 75 to the cap R, as shown in Figure 5, and in order to provide a shock absorber, this wire may be soldered to the said head R at different points, as at f' , as shown in Figure 7, so that this wire will tear the solder at the head and ease the shock, as will be herein-after described.

This soldering arrangement may be used with or substituted for the coil spring shock absorber f previously described, or where 80 light weights are expelled, the shock absorber may be omitted altogether.

The wire F has one end fastened, as at f^o , to the head R, and the adjacent parts of the wire are coiled around the front head R of the flare casing, as shown in Figure 5. This part of the wire leads to the wire loop f^2 which is connected to the parachute stays e, as shown in Figure 5, and then the free end of the wire is coiled around inside the container 85 C, and the outer end is made fast at f^3 to the container C. The operation of the device is as follows:

It is loaded into the piece indicated in dotted lines by the pistol A in Figure 1, and 90 when this piece is fired, the gases from the blank cartridge will expand in the expansion chamber B^o of the stem B' , and the flame will ignite the flare composition N' in the tube N. The gases in the chamber B^o 100 will eject the washers H, H' and H'' which will act as a piston and will cause the container C to push out the head I, as shown in Figure 1.

This container with its contents will be 105 ejected through the air a predetermined distance, as indicated in Figure 1. When the expelling charge is ignited, it will blow the washers to the rear and will blow the flare casing and the parachute out of the container, 110 as indicated progressively in Figures 2 and 3. As shown in Figure 3, the container, the flare casing and the parachute will all be connected together by the wire F, and as these three descend, the parachute will become distended 115 and will support the flare and the casing, as shown in Figure 4. In the meantime, the flare composition Q will have ignited the open end of the flare casing, and the flare 120 will burn from the bottom up, as shown in Figure 4.

While we have shown a cartridge case having a reduced stem and an enlarged loading chamber, obviously the cartridge case may be made of the same diameter throughout, if 125

desired. By having an enlarged loading chamber, a larger parachute, and a larger flare body may be discharged from the piece with a comparatively small propelling charge.

5 While any suitable form of delayed action fuse may be used for transmitting the flame from the blank cartridge G to the expelling charge M', we have shown a tube N, in which 10 the slow burning flare composition is compressed and is held, so that it will not be blown through, and at each end of this tube, we may provide lateral openings, such as 15 at n°, to ignite either the flare composition at one end, or the expelling charge at the other.

While we have described one embodiment 20 of the invention in its preferred form, it will be obvious that various changes might be made in the construction, combination and arrangement of parts, which could be used without departing from the spirit of our invention, and we do not mean to limit the invention to such details except as particularly 25 pointed out in the claims.

Having thus described our invention, what we claim and desire to secure by Letters Patent of the United States is:—

1. Fixed ammunition for use with low 20 power smooth bore firearms, having a short barrel of large calibre, said ammunition comprising a cartridge case forming an auxiliary barrel for the small arm and provided with a stem adapted to slide freely in the gun 25 barrel, with a propelling charge in said stem, the said stem having a chamber for the expansion of the gases from the propelling charge, and said cartridge case having an enlarged loading chamber in front of said stem, with 40 a projectile mounted in said loading chamber, and adapted to be ejected therefrom by the gases from the propelling charge, said projectile comprising a tube slidably mounted in the loading chamber of the cartridge case, a 45 parachute and flare mounted in said tube, an expelling charge also mounted in said tube for ejecting said parachute and flare and for igniting said flare, means for suspending said tube and said flare from said parachute as 50 they fall together through the air, and means, controlled by the firing of the small arm, for igniting said expelling charge.

2. Fixed ammunition for use with low power smooth bore firearms, having a short 55 barrel of large calibre, said ammunition comprising a cartridge case forming an auxiliary barrel for the small arm and provided with a stem adapted to slide freely in the gun barrel, with a propelling charge 60 in said stem, the said stem having a chamber for the expansion of the gases from the propelling charge, and said cartridge case having an enlarged loading chamber in front of 65 said stem, with a projectile mounted in said loading chamber, and adapted to be ejected

therefrom by the gases from the propelling charge, said projectile comprising a tube slidably mounted in the loading chamber of the cartridge case, a parachute and flare mounted in said tube, an expelling charge 70 also mounted in said tube for ejecting said parachute and flare and for igniting said flare, a wire connecting said tube and said flare to the parachute for suspending said tube and said flare from said parachute as 75 they fall together through the air, and means, controlled by the firing of the small arm, for igniting said expelling charge.

3. Fixed ammunition for use with low power smooth bore firearms, having a short barrel of large calibre, said ammunition comprising a cartridge case forming an auxiliary barrel for the small arm and provided with a stem adapted to slide freely in the gun barrel, with a propelling charge in said stem, 80 the said stem having a chamber for the expansion of the gases from the propelling charge, and said cartridge case having an enlarged loading chamber in front of said stem, with a projectile mounted in said loading chamber, and adapted to be ejected therefrom by the gases from the propelling charge, said projectile comprising a tube 85 slidably mounted in the loading chamber of the cartridge case, a parachute and flare mounted in said tube, an expelling charge also mounted in said tube for ejecting said 90 parachute and flare and for igniting said flare, a wire connecting said tube and said flare to the parachute for suspending said tube and said flare from said parachute as 95 they fall together through the air, means for lessening the shock on said wire as the parachute becomes distended, and means, controlled by the firing of the small arm, for 100 igniting said expelling charge.

4. Fixed ammunition for use with firearms, comprising a cartridge case, with a propelling charge in the rear end of said cartridge case, said cartridge case having a chamber for the expansion of the gases from the propelling charge, and said cartridge case having a loading chamber in front of said stem, with a projectile mounted in said loading chamber, and adapted to be ejected 110 therefrom by the gases from the propelling charge, said projectile comprising a tube slidably mounted in the loading chamber of the cartridge case, a parachute and a flare mounted in said tube, an expelling charge 115 for ejecting said parachute and flare and for igniting said flare, means for suspending said tube and said flare from said parachute as the parachute becomes extended and they fall together through the air, and means, controlled by the firing of the small arm, for 120 igniting said expelling charge.

5. Fixed ammunition for use with firearms, comprising a cartridge case with a propelling charge in the rear end of said car- 130

tridge case, said cartridge case having a chamber for expansion of the gases from the propelling charge, and said cartridge case having a loading chamber in front of said stem, with a projectile mounted in said loading chamber, and adapted to be ejected therefrom by the gases from the propelling charge, said projectile comprising a tube slidably mounted in the loading chamber of the cartridge case, a parachute and a flare mounted in said tube, an expelling charge for ejecting said parachute and flare and for igniting said flare, a wire connecting said tube and said flare to said parachute for suspending said tube and said flare from said parachute as the parachute becomes extended and they fall together through the air, and means, controlled by the firing of the small arm, for igniting said expelling charge.

6. Fixed ammunition for use with firearms, comprising a cartridge case with a propelling charge in the rear end of said cartridge case, said cartridge case having a chamber for the expansion of the gases from the propelling charge, and said cartridge case having a loading chamber in front of said stem, with a projectile mounted in said loading chamber, and adapted to be ejected therefrom by the gases from the propelling charge, said projectile comprising a tube slidably mounted in the loading chamber of the cartridge case, a parachute and a flare mounted in said tube, an expelling charge for ejecting said parachute and flare and for igniting said flare, a wire connecting said tube and said flare to said parachute, for suspending said tube and said flare from said parachute as the parachute becomes extended and they fall together through the air, means for lessening the shock on said wire as the parachute becomes distended, and means, controlled by the firing of the small arm, for igniting said expelling charge.

LOUIS L. DRIGGS, JR.
